United States Patent

Des. 237,931

Patented Dec. 9, 1975

237,931

KITCHEN ISLAND TABLE

Carl Brandenfels, 102 SE. Santosh,
Scappoose, Oreg. 97056

Filed June 24, 1974, Ser. No. 482,318

Term of patent 14 years

Int. Cl. D6—03

U.S. Cl. D6—179

Fig. 2

Fig. 1

FIG. 1 is a perspective view of a kitchen island table embodying the new design; and

FIG. 2 is a top plan view thereof.

The side of the table not shown is a mirror image of the side shown.

I claim:

The ornamental design for a kitchen island table, as shown and described.
